US00D723785S

(12) **United States Design Patent**
Miner

(10) **Patent No.:** **US D723,785 S**
(45) **Date of Patent:** ** *Mar. 10, 2015

(54) **SHOE OUTSOLE**

(71) Applicant: **NIKE, Inc.**, Beaverton, OR (US)

(72) Inventor: **Mark C. Miner**, Portland, OR (US)

(73) Assignee: **NIKE, Inc.**, Beaverton, OR (US)

(*) Notice: This patent is subject to a terminal disclaimer.

(**) Term: **14 Years**

(21) Appl. No.: **29/492,577**

(22) Filed: **May 31, 2014**

Related U.S. Application Data

(63) Continuation of application No. 29/481,800, filed on Feb. 10, 2014, now abandoned, which is a continuation of application No. 29/465,636, filed on Aug. 29, 2013, now abandoned, which is a continuation of application No. 29/443,440, filed on Jan. 17, 2013, now abandoned, which is a continuation of application No. 29/429,338, filed on Aug. 9, 2012, now abandoned, which is a continuation of application No. 29/414,576, filed on Feb. 29, 2012, now abandoned.

(57) **CLAIM**

The ornamental design for a shoe outsole, as shown and described.

DESCRIPTION

FIG. 1 is a bottom view of a shoe outsole showing my new design;

FIG. 2 is a front perspective view thereof; and,

FIG. 3 is a lateral side view thereof.

The broken lines inside of the photographic area are for environmental purposes only and for no part of the claimed design. The broken lines showing the remainder of the shoe are for environmental purposes only and form no part of the claimed design.

1 Claim, 3 Drawing Sheets
